UNITED STATES PATENT OFFICE.

WILLIAM HAYNES, OF ATLANTA, GEORGIA, ASSIGNOR TO DRAPER COMPANY, OF PORTLAND, MAINE.

CUT SIGNAL OR INDICATOR FOR LOOMS.

SPECIFICATION forming part of Letters Patent No. 753,980, dated March 8, 1904.

Application filed December 2, 1903. Serial No. 183,450. (No model.)

To all whom it may concern:

Be it known that I, WILLIAM HAYNES, a citizen of the United States, residing at Atlanta, county of Fulton, State of Georgia, have invented an Improvement in Cut Signals or Indicators for Looms, of which the following description, in connection with the accompanying drawing, is a specification, like letters on the drawing representing like parts.

10 This invention has for its object the production of simple means for automatically indicating or signaling to a weaver when a certain length or "cut" of cloth has been woven, so that the cut can be detached and a new one 15 begun.

It is now common practice to indicate, usually by a paint-mark on the warp, during the beaming or other preparatory operation a certain number of yards of warp, these marks 20 being termed "cut-marks," so that when one of them appears in the woven cloth the weaver knows a cut has been completed. When a weaver has charge of a number of looms, which may be from twelve to sixteen or more in the 25 case of automatic looms, the cut-mark may pass unnoticed unless considerable care is exercised. By my present invention a signaling or indicating device is automatically moved into operative position when the cut has been 30 woven, so that the weaver can stop the loom and remove the same.

The novel features of my invention will be 35 fully described in the subjoined specification and particularly pointed out in the following claims.

The drawing represents in transverse section a sufficient portion of a loom to be understood with one embodiment of my invention applied thereto, the indicating or signaling device being in normal position.

I have shown my invention applied to an automatic loom of the Northrop type, such as forms the subject-matter of United States Patent No. 529,940, the stand A⁷ for the filling feeler or hopper being shown mounted on the breast-beam A⁴⁰. The take-up roll T and the cloth-roll shaft G, having its journals mounted in the upper ends of rack-bars g^x, which slide in slots in the stands F, secured

to the loom-frame A, may be and are all substantially as shown in United States Patent No. 610,636, to which reference may be had, the accumulation of cloth on the shaft G serving to gradually press the rack-bars g^x downward, as provided for in said patent. 50

I have herein shown a signal-target or indicator D, secured to a lever d, fulcrumed at d^x on the inner face of the stand A⁷, the forward end of the lever being weighted at d' to overbalance the weight of the indicator. The latter may conveniently be made of sheet metal and painted red or of some color which will attract attention. Normally the indicator is in the position shown in full lines, a stoppin 5 limiting its downward movement, the 60 hopper-stand substantially hiding the indicator from view. A latch e is fulcrumed at e^x on the stand and is adapted to extend beneath the weight d' and retain it in elevated position with the indicator in inoperative position. The latch has an attached forwardly-extended tail e', pivotally connected with a depending link e², bent to clear the shield-like part A³⁰ of the breast-beam and extending below it to a point considerably lower than the roll of 70 cloth. The lower end of the link passes loosely through a hole e³ (see dotted lines) in a trip e⁴, fulcrumed at e⁵ on a bracket h, adjustably secured to one of the stands F by a clamp-bolt h', which passes through an upright elongated 75 slot h³ in the bracket. Nuts or collars 3 3, fast on the link above and below the trip, connect the latter with the link. The inner end of the trip is provided with a lateral lug e⁶, 80 located in the path of movement of a releasing device, shown as a finger m, secured rigidly to the adjacent slide g^x above the trip. The weight of the link e² is sufficient to maintain the latch e pressed upward against the weight d', with the lever d resting against the stop 85 90, as shown in the drawing. As the diameter of the cloth wound upon the shaft G increases the rack-bars g^x gradually move downward, and when the finger m engages the lug e⁶ the trip e⁴ is rocked on its fulcrum, raising its outer end, and thereby lifting the link e². Consequently the tail e' is raised and the latch e depressed and moved out of engagement 95

with the weight *d*, which immediately descends, elevating the indicator *D* into dotted-line position in plain view of the weaver, above the filling-feeder. The weaver then 5 knows that a cut has been completed. If the cut is, say, forty yards, the trip *e* is set by means of the clamp-bolt *h*' and bracket *h* at such a distance below the releasing-finger *m* (when the cloth-roll shaft *G* is empty) that 10 when forty yards of cloth have been wound up on said shaft *G* the indicator will be moved into indicating position. When a cut is begun, the weaver sets the indicator in inoperative or normal position and with the latch *e* be- 15neath the weight.

By a device of this character the weaver is not required to pay close attention to the cloth to discover the cut-mark, and can devote his time and attention more completely to other 20 matters.

Having described my invention, what I claim as new, and desire to secure by Letters Patent, is—

1. In a loom, take-up mechanism, including 25 a shaft on which the cloth is wound, a signal or indicator, means coöperating therewith by which it is normally maintained in non-indicating position, and separate means to automatically and positively interrupt coöperation 30 of said first-mentioned means and the signal or indicator, to thereby render the latter operative when a predetermined length of cloth has been wound upon said shaft.

2. In a loom, take-up mechanism, a visual 35 indicator, means to retain it normally in non-indicating position, and means operative automatically when a predetermined length of cloth has been taken up to render inoperative the retaining means and thereby to effect 40 movement of the indicator into a conspicuous position.

3. In a loom, take-up mechanism, a visual 45 indicator, a device to move it into indicating position, means, including a latch, to retain the indicator in non-indicating position, and a releasing device for said means, governed by or through the take-up mechanism, to render the latch inoperative when a predetermined length of cloth has been taken up.

4. In a loom, take-up mechanism, including 50 a shaft on which the cloth is wound, sliding supports therefor, a pivotally-mounted indicator, a device to move it into indicating position, a latch to engage said device and retain the indicator in non-indicating position, 55 a trip connected with the latch, and a releasing device for the trip, mounted on one of the sliding supports, to render the latch inoperative when a predetermined length of cloth has been wound on said shaft.

5. In a loom, take-up mechanism, including 60 a shaft on which the cloth is wound, sliding supports therefor, a pivotally-mounted indicator, a device to move it into indicating position, a latch to engage said device and retain the indicator in non-indicating position, 65 a trip connected with the latch, means to adjust the trip for different lengths of "cut," and a releasing device for the trip, mounted on one of the sliding supports, to render the latch inoperative when a "cut" has been wound on the shaft.

6. In an automatic loom provided with a stand for a filling-feeder, a "cut" indicator 75 pivotally mounted thereon and having an attached weight to move it into indicating position, a latch to engage the weight and retain the indicator in non-indicating position, take-up mechanism, and means to automatically retract the latch when a predetermined length 80 of cloth, or "cut," has been taken up.

7. In a loom, take-up mechanism, a visual 85 indicator, a device to move it into indicating position, means, including a latch and an adjustable trip connected therewith, to normally retain the indicator in non-indicating position, and a movable finger to engage the trip and release the indicator from control of the latch when a predetermined length of cloth has been woven.

In testimony whereof I have signed my name to this specification in the presence of two subscribing witnesses.

WILLIAM HAYNES.
